(57) **CLAIM**

The ornamental design for a “football-shaped cocktail shaker”, as shown and described.

DESCRIPTION

FIG. 1 is a front elevational view of the football-shaped cocktail shaker, showing my new design;

FIG. 2 is a right side elevational view thereof (and a mirror image of the left side elevation);

FIG. 3 is a top view thereof (and a mirror image of the bottom view);

FIG. 4 is a back view thereof;

FIG. 5 is a front exploded view of the football-shaped cocktail shaker showing a removable cap-portion repositioned to an alternate (offset) position;

FIG. 6 is a top exploded view of the football-shaped cocktail shaker in the alternate position of FIG. 5; and,

FIG. 7 is a bottom exploded view of the football-shaped cocktail shaker in the alternate position of FIG. 5.

The arrow depiction of FIG. 5 illustrates preferred alignment of parts and forms no part of the claimed design.
